S. B. McKNIGHT,
GATE LATCH,
APPLICATION FILED MAY 21, 1919.

1,326,278.

Patented Dec. 30, 1919.

UNITED STATES PATENT OFFICE.

SAM BELL McKNIGHT, OF MILANO, TEXAS.

GATE-LATCH.

1,326,278.

Specification of Letters Patent.

Patented Dec. 30, 1919.

Application filed May 21, 1919. Serial No. 298,758.

To all whom it may concern:

Be it known that I, SAM B. McKNIGHT, a citizen of the United States, residing at Milano, in the county of Milam and State of Texas, have invented certain new and useful Improvements in Gate-Latches, of which the following is a specification.

The invention relates to fastening means designed more especially for farm gates and 10 which may be used to advantage in swinging closures of any type and for any desired purpose.

The invention provides novel fastening means embodying a movable latch member 15 of annular form and a peculiar support therefor of such structure as to be fashioned from a metal strap or plate of peculiar form having a portion bent in a unique manner to provide a loop-shaped member to

20 which the latch member is directly applied.

The drawing illustrates a preferred embodiment of the invention. However, it is to be understood that in adapting the same to meet different conditions, various changes 25 in the form, proportion, and minor details of construction may be resorted to without departing from the nature of the invention as claimed hereinafter.

Referring to the drawing hereto attached, 30 Figure 1 is a perspective view of a gate latch embodying the invention, the dotted lines illustrating a portion of the gate and gate post.

Fig. 2 is a sectional detail, the dotted lines 35 illustrating the operation of the latch when closing the gate.

Fig. 3 is a detail view of the blank from which the bracket or latch supporting member is formed.

40 Corresponding and like parts are referred to in the following description and indicated in the several views of the drawing by like reference characters.

The numeral 1 designates part of a gate 45 post which is located at one side of the gate opening and against which the gate closes. The numeral 2 indicates a portion of the gate to which in the present instance a latch bar 3 is attached and projects beyond the end of 50 the gate to engage the gate post 1 and limit the closing of the gate when the latter is swung to.

The latch member 4 is of annular form and consists of a ring of suitable proportions and construction. The latch member 55 4 is carried by a support 5 which is of loop

form, as shown most clearly in Fig. 1, the member being disposed in the space formed between the element comprising the support 5. Two pins 6 extend across the space of 60 the support and their ends are received in openings formed in the elements comprising the loop. The latch member 4 is free to swing upwardly and rearwardly when closing the gate, as indicated by the dotted lines 65 in Fig. 2, but is prevented from swinging forwardly and upwardly by reason of its engagement with the pins 6 and the forward end of the loop-shaped support 5, as indicated by the full lines in Fig. 2. The 70 space inclosed by the loop-shaped support 5 is of such dimensions as to admit of the rearward and upward movement of the latch member, but to prevent its forward and upward movement, thereby holding the gate 75 when closed. The loop-shaped support 5 is part of a metal strap or plate 7, as indicated most clearly in Figs. 1 and 3. An end portion of the plate or strap has a longitudinal cut 8 extending inward for some distance 80 parallel with the edges of the strap. The portions 9 and 10 separated by the longitudinal cut 8 are of different lengths, the part 10 being of such length as to admit of a portion being folded to provide the loop- 85 shaped support, 5, which latter is bent to project outwardly from the plate 7 at a right angle, the inner portion of the part 10 being given a one-quarter twist, as indicated at 11 to enable the space between the 90 folded portions of the part 10 occupying a vertical position so that the latch member 4 may move vertically. A block 12 closes the space formed at one end between the folded portions of the part 10. said block being retained in position by means of a fastening 13 which also connects the spaced ends of the folded portions. The fastenings 6 connect the folded portions of the part 10 95 near the outer end or fold, thereby strengthening the part 5 and forming supporting means for the latch member 4. The plate 7 and the part 9 are formed with openings 14 which receive suitable fastenings by which the latch member support is attached 105 to the gate post 1 or like part.

In practice the parts of the fastening are attached to the gate post and gate respectively, as indicated most clearly in Fig. 1. Under normal conditions the latch member 110 4 occupies a pendent position and is supported upon the fastenings 6. Upon closing the

gate the projecting portion of the latch bar 3 strikes the outer portion of the latch member 4, thereby causing the latter to swing rearwardly and upwardly upon or about the 5 forward or outer fastening 6. When the latch bar clears the latch member 4 the latter drops into the position indicated by full lines in Fig. 2 and occupies a position in front of the latch bar which latter is disposed between the gate post and the latch member 4. The gate cannot be opened by pressure thereagainst because the latch member 4 binds against the outer closed end of the loop-shaped support 5 and tends to swing 10 about the rear fastening 6, hence the greater the pressure against the rear portion of the latch member 4 the same will bind proportionately against the closed end of the support 5 as will be readily understood.

20 The foregoing description and the drawing have reference to what may be considered the preferred, or approved form of my invention. It is to be understood that I may make such changes in construction and ar-

angement and combination of parts, materials, dimensions, et cetera, as may prove expedient and fall within the scope of the appended claim.

Having thus fully described my invention, what I claim as new and desire to secure by Letters Patent is:—

A gate latch, comprising a metal strap having a longitudinal cut extending inwardly from one end and having an end portion of one of the parts separated by the 35 longitudinal cut removed and having the other part doubled upon itself to form a loop which is bent outwardly at a right angle to the plate and given a one-quarter twist, pins connecting the folded portion of 40 the strap and an annular latch supported on the pins.

In testimony whereof I affix my signature in presence of two witnesses.

SAM BELL McKNIGHT.
